UNITED STATES PATENT OFFICE

152,381

DESIGN FOR A SCARF OR SIMILAR ARTICLE

Eugen Tanzer, New York, N. Y.

Application August 15, 1947, Serial No. 140,885

Term of patent 7 years

(Cl. D3—12)

To all whom it may concern:

Be it known that I, Eugen Tanzer, a citizen of no country, residing in New York city, county of Bronx, and State of New York, have invented a new, original, and ornamental Design for a Scarf or Similar Article, of which the following is a specification, reference being had to the accompanying drawing, forming part thereof, wherein the figure is a plan view of a scarf showing my new design.

The essential features of my design reside in the portions shown in full lines.

I claim:

The ornamental design for a scarf or similar article, substantially as shown and described.

EUGEN TANZER.
